UNITED STATES PATENT OFFICE.

EARLE M. GIBSON AND CHARLES W. STAPLES, OF WASHBURN, MAINE.

FOOT THROTTLE OR ACCELERATOR FOR AUTOMOBILES.

1,131,830.

specification of Letters Patent. Patented Mar. 16, 1915.

Application filed May 27, 1914. Serial No. 841,300.

To all whom it may concern:

Be it known that we, EARLE M. GIBSON and CHARLES W. STAPLES, citizens of the United States, residing at Washburn, in the 5 county of Aroostook and State of Maine, have invented certain new and useful Improvements in Foot Throttles or Accelerators for Automobiles, of which the following is a specification, reference being had to the 10 accompanying drawings.

This invention relates to foot throttles or accelerators for use on automobiles, and more particularly to those of the "Ford" type.

15 The object of the invention is to provide an attachment of this character which may be combined with a machine already in use without requiring any extended change in its structural arrangement, and in the use of 20 which the foot of the driver may be employed for controlling the throttle independent of the hand throttle, or vice versa, there being no interference between the operation of the two throttle members.

25 A further object is to provide an attachment of this character which will permit the removal or replacing of the foot boards without necessitating the detachment or positioning of nuts, cotter pins, bolts, or other 30 fastenings, whereby access to the throttle may be obtained in a ready and convenient manner.

With the above and other objects in view, as will appear as the nature of the invention 35 is better understood, the same consists in the novel features of construction and arrangement of parts of a foot throttle or accelerator for automobiles, as will be hereinafter fully described and claimed.

40 In the accompanying drawings forming a part of this specification, and in which like characters of reference designate corresponding parts; the figure is a view in perspective of the attachment.

45 Referring to the drawings, 1 designates an ordinary hand throttle rod, one end of which is connected with the throttle lever 2 of an ordinary throttle valve 3, this end of the rod having connected with it one end 50 of a coiled spring 4, the other end of which is connected with the side of the car frame.

At the end of the rod 1 opposite that carrying the spring 4 is secured the usual hand throttle rod attachment 5, nuts 6 screwed 55 on the adjacent end of the rod 1 serving to adjust the length of the latter, and also to

act as a stop to give proper leverage to the attachment 5.

Secured to the rod 1, in any preferred manner, is a clip 7 through which loosely 60 projects one end of a rod 8, the other end of which is bent at an angle, and terminates in a flattened head 9. The angle rod 8 at its bend 10 is pivoted between a two-armed bracket 11 secured to the under side of the 65 foot-board F, the connection between the bracket and the lever being effected by a bolt 12. The head 9 is designed to be engaged by the foot bracket pedal of the automobile, so that it is always under the control 70 of the operator.

In operation, pressure on the head 9 causes the rod 8 to swing on the bolt 12, thereby imparting a swinging movement to the free end of the rod or that projecting 75 through the clip 7, and imparts a sidewise movement of the throttle 1 thereby to shift the throttle rod lever 2 and effect opening of the throttle, the spring 4 operating automatically to close the throttle when pressure 80 is removed from the head 9. As the rod 8 is free to slide within the clip 7, and is not held against endwise movement relative thereto by a cotter pin, nut, or the like, the foot-board F may readily be removed when 85 occasion requires, to gain access to the engine or the like. By the connection of the hand throttle rod or lever already on the car with the attachment 5, and by the movement of the hand throttle on the steering 90 wheel, the throttle rod 1 may be moved manually thus opening the throttle valve, and when the hand throttle on the steering wheel is released, the spring 4 will automatically close the throttle valve. It will 95 thus be obvious that the foot throttle may be used independent of the hand throttle, and vice versa, the arrangement being such that there will be no interference between the two.

100 This foot throttle or accelerator gives a steady throttle when the throttle valve is closed, open, or partially opened, because the spring 4, by being attached to the throttle rod 1 and the car frame, holds the 105 throttle rod steadily against the adjacent nuts 6.

To adapt this attachment to the throttle will require no extra parts or attachments on the carburetor, as the original throttle rod is 110 simply removed and the throttle rod 1 substituted therefor.

From the foregoing description it will be seen that while the improvements described are simple in character, they will be thoroughly efficient for the purposes designed, and will result in the presentation of an attachment that will be at once durable, cheap and practical.

Having thus described our invention, what we claim is:

10. 1. In a motor vehicle, the combination with a throttle actuating member, of a removable foot board, and an operating member mounted upon the foot board having engagement with the throttle actuating member, said members being detached from engagement with each other upon the removal of the foot board and operating member.
15. 2. In a motor vehicle, a throttle actuating member, a rod connected with one end of the member, a clip secured to the rod adjacent its other end, said clip having a laterally disposed lug, a foot board, a bell crank lever pivotally connected to the under side of the foot board, said lever having one arm thereof slidably disposed through said aperture lug, whereby said lug will be moved to operate the throttle actuating member, and whereby the arm of the bell crank lever may be disengaged from the rod 30 by the removal of the foot board together with the bell crank lever.
20. 3. In a motor vehicle, a throttle actuating member, a rod connected at one end to said member, a clip secured to the rod adjacent its other end and having a laterally
25. 4. In a motor vehicle, the combination with a throttle valve operating element comprising a longitudinally shiftable rod, of a clip loosely embracing the rod at one end and adapted to be connected to hand operated means for longitudinally shifting the rod, a stop upon the extremity of the rod and adjacent to the clip, and with which 35 said clip is adapted to engage to shift the rod, a clip mounted upon the intermediate portion of the rod and through which the rod is freely shiftable, a lever movable in a plane parallel to the length of the rod and 40 passing loosely through said clip, and a spring acting to retract the rod.

disposed apertured lug, a removable foot board, a bell crank lever pivotally mounted upon the under side of the foot board, said lever constituting a pedal, one arm of the lever being of uniform diameter toward its 45 extremity, said extremity passing through and being slidably disposed in the aperture of the lug whereby the rod may be shifted on actuation of the bell crank lever and said lever may be disengaged from the rod upon the removal of the foot board with the bell crank lever.

4. In a motor vehicle, the combination with a throttle valve operating element comprising a longitudinally shiftable rod, of a clip loosely embracing the rod at one end and adapted to be connected to hand operated means for longitudinally shifting the rod, a stop upon the extremity of the rod and adjacent to the clip, and with which 50 said clip is adapted to engage to shift the rod, a clip mounted upon the intermediate portion of the rod and through which the rod is freely shiftable, a lever movable in a plane parallel to the length of the rod and 55 passing loosely through said clip, and a spring acting to retract the rod.

In testimony whereof we hereunto affix our signatures in the presence of two witnesses.

EARLE M. GIBSON.

CHARLES W. STAPLES.
